UNITED STATES PATENT OFFICE.

CLARENCE CARSON, OF DETROIT, MICHIGAN, ASSIGNOR, BY MESNE ASSIGNMENTS,
TO CHRYSLER CORPORATION, A CORPORATION OF DELAWARE.

DESIGN FOR A COMBINED VEHICLE BODY, HOOD, AND FENDERS.

Application filed January 3, 1927. Serial No. 20,265. Term of patent 3½ years.

To all whom it may concern:

Be it known that I, CLARENCE CARSON, a citizen of the United States, residing at Detroit, in the county of Wayne and State of Michigan, have invented a new, original, and ornamental Design for Combined Vehicle Body, Hood, and Fenders, of which the following is a specification, reference being had to the accompanying drawing, forming part thereof.

In the figures, Figure 1 is a side elevational view of a combined vehicle body, hood and fenders showing my new design, Figure 2 is a front elevational view of the same and Figure 3 is a rear elevational view of the same.

I claim:

The ornamental design for a combined vehicle body, hood and fenders as shown.

CLARENCE CARSON.
